UNITED STATES PATENT OFFICE

141,317

DESIGN FOR A DECK OF PLAYING CARDS

Marsh M. Smith, Sr., Fontana, Calif.

Application December 26, 1944, Serial No. 117,077

Term of patent 14 years

(Cl. D34—13)

To all whom it may concern:

Be it known that I, Marsh M. Smith, Sr., a citizen of the United States, residing at Fontana, in the county of San Bernardino and State of California, have invented a new, original, and ornamental Design for Deck of Playing Cards, of which the following is a specification, reference being had to the accompanying drawings, forming part thereof.

Figs. 1 and 2 are face views of the cards of one complete suit of the deck of playing cards showing my new design. There are four suits in the deck which differ from each other merely in colors. The backs of the cards are conventional.

I claim:

The ornamental design for a deck of playing cards, as shown and described.

MARSH M. SMITH, SR.
